PUMP

Charles W. Sproull, Houston, Tex.; Edith M. Sproull, executrix of said Charles W. Sproull, deceased

Application February 23, 1946, Serial No. 649,461

6 Claims. (Cl. 103—174)

1

This invention relates to a pump specially adapted for pumping fluid in a substantially continuous stream.

An object of the invention is to provide a radial pump having a plurality of radially mounted cylinders therein with pistons in the cylinders arranged to be driven from a common driving shaft.

Another object of the invention is to provide a novel type of frame wherein the cylinders and the piston driving mechanism are mounted.

It is a further object of the invention to provide a pump of the character described wherein the piston driving mechanism may be readily adjusted to control the stroke of the pistons.

Other objects and advantages will be apparent from the following specification which is illustrated by the accompanying drawings, wherein:

Figure 1 is a horizontal sectional view taken on the line 1—1 of Figure 2; and

Figure 2 is a vertical sectional view taken on the line 2—2 of Figure 1.

Referring now more particularly to the drawings wherein like numerals of reference designate the same parts in each of the figures, the numeral 1 designates a gear case which is tubular in form and which is supported on any suitable base, as 2. Mounted on the gear case and suitably secured thereto there is a frame comprising a supporting plate 3 with the concentric upstanding outer and inner annular flanges 4 and 5 secured thereto in any preferred manner.

Extending through flanges and suitably secured thereto there are a plurality of radial cylinders 6 wherein the pistons 7 are mounted to reciprocate.

These pistons are connected to a ring 8 by means of the connecting rods 9 whose outer ends are pivoted to the respective pistons and whose inner ends are pivotally connected to said ring 8.

Within the gear case 1 and fastened to the plate 3 there is a bearing 10 in which the vertical shaft 11 is mounted to rotate.

Fixed on the lower end of the shaft 11 there is a large bevel gear wheel 12 which is in mesh with and driven by a bevel pinion 13 which is fixed on the inner end of a suitable driving shaft 14. This shaft 14 is mounted to rotate in a radial bearing 15 in the wall of the gear case 1 and is driven from any suitable source of power.

The shaft 11 is concentric with the flanges 4 and 5 and is centrally located with respect to the cylinders mounted in said flanges.

Splined on the upper end of the shaft 11 there is an eccentric disc 16 which is circular in shape and fitted around the disc 16 there is an eccentric

segment 17 which may be bolted to the disc 16 by a series of bolts 18 or said segment 17 may be otherwise adjustably secured to the disc 16. The segment 17 is circular in shape but it is eccentric with respect to the disc 16 and by loosening the bolts 18 said segment may be adjusted circumferentially about the disc 16.

Said disc 16 and the segment 17 form an eccentric which rotates with the shaft 11.

This eccentric is mounted within the ring 8 and said ring and eccentric have registering raceways in which the anti-friction balls 19 are mounted.

The segment 17, the ring 8 and the balls 19 may be assembled by leaving a gate in one of said adjacent parts for inserting the balls, which gate may then be closed, in any preferred manner, by welding or otherwise.

As the eccentric rotates with the shaft 11 the ring 8 will be oscillated and will impart corresponding strokes to the pistons in the cylinders 6.

Connected to the outer ends of the respective cylinders are the manifolds 20.

Leading into corresponding ends of the manifolds 20 are the intake pipes 21 which are controlled by the inwardly opening intake valves 22. Leading outwardly from the opposite ends of said manifolds are the outlet pipes 23 which are controlled by the corresponding outlet valves 24.

The intake pipes 21 are connected into the common inlet manifold 25 with which the inlet suction line 26 is connected and the outlet pipes 23 are connected into a common outlet manifold 27 into which the discharge line 28 is connected.

Accordingly upon rotation of the eccentric, fluid will be constantly drawn in through the suction line 26 and discharged through the discharge line 28 and the capacity of the pump may be regulated by the adjustment of the eccentric segment 17, as hereinabove explained.

An anti-friction bearing assembly 29 is provided between the hub of the disc 6 and the frame of the pump.

The drawings and description are illustrative merely while the broad principle of the invention will be defined by the appended claims.

What I claim is:

1. A pump of the character described comprising a gear case, a frame mounted thereon having upstanding outer and inner flanges, radial cylinders extended through, and secured to the flanges, pistons reciprocable in the cylinders, an oscillatable ring, connecting rods pivoted at their outer ends to the pistons and at their inner ends to the ring, an eccentric within the ring, a shaft splined to the eccentric, driving

gearing in the gear case for driving the shaft and eccentric to oscillate the ring and reciprocate the pistons, intake and outlet pipes connected into the outer ends of the cylinders, inlet and outlet manifolds into which the respective intake and outlet pipes are connected, valves controlling the intake and outlet pipes, a suction line entering the inlet manifold and a discharge line leading from the outlet manifold.

2. A pump of the character described comprising a frame having concentric upstanding flanges, radial cylinders extended through and anchored to said flanges, pistons in the cylinders, an oscillatable ring, connecting rods pivoted at their outer ends to the pistons and at their inner ends to said ring, an eccentric within the ring, said eccentric being adjustable to vary the range of oscillation of the ring, means for driving the eccentric, a valve controlled intake pipe entering the outer end of each cylinder, a valve controlled outlet pipe leading from the outer end of each cylinder, inlet and outlet manifolds with which the respective intake and outlet pipes are connected, a suction line entering the inlet manifold and a discharge line leading from the outlet manifold.

3. A pump of the character described comprising a frame having upstanding outer and inner flanges, radial cylinders extended through, and secured to the flanges, pistons reciprocable in the cylinders, an oscillatable ring, connecting rods pivoted at their outer ends to the pistons and at their inner ends to the ring, an eccentric within the ring, a shaft splined to the eccentric, driving gearing for driving the shaft and eccentric to oscillate the ring and reciprocate the pistons, said eccentric being adjustable to vary the range of the eccentric, to thereby vary the stroke of the pump, intake and outlet pipes connected into the outer ends of the cylinders, inlet and outlet manifolds into which the respective intake and outlet pipes are connected, valves controlling the intake and outlet pipes, a suction line entering the inlet manifold and a discharge line leading from the outlet manifold.

4. A pump of the character described comprising, a gear case, a frame with supporting plate mounted thereon, said supporting plate having concentric upstanding outer and inner annular flanges secured thereto, radial cylinders extended through the flanges, pistons reciprocable in the cylinders, an oscillatable ring, connecting rods pivoted at their outer ends to the pistons and at their inner ends to said ring, an eccentric mounted within the ring and being adjustable to vary the range of oscillation of the ring, a shaft mounted within a bearing secured within the gear case, driving gearing in the gear case for driving the shaft, said shaft being splined to said eccentric to oscillate the ring and reciprocate the pistons, a valve controlled intake pipe entering the outer end of each cylinder, a valve controlled outlet pipe leading from the outer end of each cylinder, inlet and outlet manifolds with which the respective intake and outlet pipes are connected, a suction line entering the inlet manifold and a discharge line leading from the outlet manifold.

5. A pump of the character described com-

prising, a frame with supporting plate secured thereto, concentric upstanding flanges secured to said plate, a plurality of radial cylinders extended through and anchored to said flanges, 5 pistons in the cylinders, a shaft concentric with said flanges and centrally located with respect to said cylinders, an oscillatable ring and connecting rods pivoted at their outer ends to the pistons and at their inner ends to the ring, an eccentric disc splined to said shaft and mounted within the ring, an eccentric segment adjustably secured to the disc, to vary the range of the disc and thereby to vary the stroke of the pump, driving gearing for rotating the shaft 10 and said eccentric in order to oscillate the ring and reciprocate the pistons, intake and outlet pipes connected into the outer ends of the cylinders, inlet and outlet manifolds into which the respective intake and outlet pipes are connected, valves controlling the intake and outlet pipes, a suction line entering the inlet manifold and a discharge line leading from the outlet manifold.

6. A pump of the character described comprising, a frame with supporting plate secured thereto, concentric upstanding flanges secured to said plate, a plurality of radial cylinders extended through and anchored to said flanges, pistons in the cylinders, a shaft concentric with 15 said flanges and centrally located with respect to said cylinders, an oscillatable ring and connecting rods pivoted at their outer ends to the pistons and at their inner ends to the ring, an eccentric splined to said shaft and mounted within the ring, said eccentric and ring having registering raceways in which antifriction balls are mounted, an adjustable segment mounted around said eccentric to vary the range of the eccentric and thereby to vary the stroke of the 20 pump, driving gearing for rotating the shaft and said eccentric to oscillate the ring and reciprocate the pistons, intake and outlet pipes connected into the outer ends of the cylinders, inlet and outlet manifolds into which the respective intake and outlet pipes are connected, 25 valves controlling the intake and outlet pipes, a suction line entering the inlet manifold and a discharge line leading from the outlet manifold.
